UNITED STATES PATENT OFFICE.

JAMES TIMMS, OF COLUMBUS, OHIO, ASSIGNOR TO THE BUCKEYE MALLEABLE IRON AND COUPLER COMPANY, OF SAME PLACE.

CENTER-PLATE FOR CARS.

SPECIFICATION forming part of Letters Patent No. 595,681, dated December 14, 1897.

Application filed February 4, 1897. Serial No. 622,037. (No model.)

To all whom it may concern:

Be it known that I, JAMES TIMMS, of Columbus, in the county of Franklin and State of Ohio, have invented certain new and useful

5 Improvements in Center-Plates for Cars; and I do hereby declare the following to be a full, clear, and exact description of the invention, such as will enable others skilled in the art to which it appertains to make and use the same.

10 My invention relates to an improvement in center-plates for cars, the object being to provide a strong plate, one capable of sustaining great weight and heavy strains, to which center or bolster plates are ordinarily subjected.

15 With this end in view my invention consists in certain novel features of construction and combinations of parts, as will be herein-after more fully described, and pointed out 20 in the claims.

In the accompanying drawings, Figure 1 is a top plan view of my improvement. Fig. 2 is a bottom plan view of the same, and Fig. 3 is a sectional view.

25 A represents my improved center-plate, provided centrally on its bottom face with the usual depending annular seat 1, the end portions of said bottom face being provided with a series of strengthening-ribs 2, which latter

30 are preferably located as illustrated in Fig. 2 of the drawings. The upper or top face of center-plate A is closed, as shown at 3, and has projecting therefrom the side flanges 4, which latter are adapted to embrace the side 35 edges of a bolster when in its operative position, whereby lateral movement of said plate is prevented. The casting thus described is practically solid, with the exception of the hollow chamber formed between annular seat

40 1 and the closed upper face 3, the form of said

chamber being substantially the form of said annular seat 1.

As an additional means for strengthening my improved center-plate a series of posts or ribs 5 are located in the hollow chamber above 45 referred to. These ribs or posts are integral with and connect the closed upper face 3 and annular seat 1, thus affording additional strength at this point. However, if desired, ribs or posts 5 may be dispensed with, as the 50 closed upper face 3 will practically prevent crushing at this part of the plate.

From the foregoing it will be seen that a strong and durable center-plate is secured, and by reason of its closed upper face is adapted 55 to support great weight and withstand unusual and very severe usage, to which these plates are occasionally subjected.

Having fully described my invention, what I claim as new, and desire to secure by Letters Patent, is—

1. A center-plate for cars comprising a flat top plate and a hollow depending annular seat on its lower side, the plate provided with a central hole for the king-bolt, and the hollow 65 annular seat opening into the said king-bolt hole.

2. A center-plate for cars comprising a flat top plate, and a hollow depending annular seat on its lower side, said seat provided with 70 internal posts, the plate provided with a central hole for the king-bolt, and the hollow annular seat opening into the said king-bolt hole.

In testimony whereof I have signed this specification in the presence of two subscribing witnesses.

JAMES TIMMS.
